UNITED STATES PATENT OFFICE.

KARL MISCHKE, OF ZURICH, SWITZERLAND, ASSIGNOR TO DURKOPPWERKE A.-G., OF BIELEFELD, GERMANY.

SEWING MACHINE FOR MAKING FESTOONS.

Application filed May 28, 1925, Serial No. 33,478, and in Switzerland June 4, 1924.

The present invention relates to sewing machines for making festoons, of the type provided with a cross-slide and a member for cutting the edge of the festoons obliquely arranged to the vertical plane of the needles, so that the point of intersection between the axis of the cutting member and the vertical plane of the needles is in the plane of movement of the material.

Repeated attempts have been made to provide sewing machines which sew the festoons and simultaneously cut the edges of the fabric. For sewing festoons at least two needles are required, one of which, the edge needle, penetrates into the fabric at the outer edge of the festoon whilst the other needle is the sewing needle which penetrates into the fabric at the inner edge of the festoon. It is only possible to sew and cut edges and arcs when the cutting is performed at exactly the same spot in which the edge needle stitches into the fabric when sewing around the latter. The cutting organ must be small so that the acute corners present with festoons can be cut. To solve this problem, the cutting member is arranged obliquely to the festoon needles whereby the axis of the cutting member intersects the plane in which the fabric is moved so that the needle stitches exactly at the spot in which the cutting member cuts the fabric. As with this proposal the lower end of the cutting member, which is very thin cuts freely and without being guided into the fabric the cut is not exact enough. Further it has been proposed to provide an extension on the cutting knife to obtain a guidance for the latter and the knife has been pressed by means of a spring against the edge of an aperture through which the knife passed when cutting. The cooperation of the knife with the edge of the aperture was intended to perform a good cut also in case the fabric was difficult to be cut and the knife got blunt. With this arrangement the knife cuts at another spot than that at which the needle stitches the fabric for sewing around the latter and a perfect cutting was therefore not obtained; the design of the known machine did not permit a coincidence of the point at which the edge needle stitches into the fabric with the point at which the knife cuts.

Furthermore with machines for sewing

festoons it is of utmost importance that the fabric is securely shifted or transported in the correct manner. With the known machines of this type either only an upper fabric shifting device or a lower fabric shifting device or both have been provided. With machines for sewing button holes the movement of a longitudinal slide within a transverse slide, the so-called cross-slide, is known as well as the provision of means for holding or pressing the fabric which bear on the latter during the sewing of a button hole.

In order to ensure a safe and correct transport or feed of the fabric to be provided with festoons by means of an upper and a lower fabric shifting device, the fabric shifting device on the machine according to the present invention having a cross slide is provided with a swingably mounted lever for pressing the fabric, the lever being raised and lowered onto the fabric in regular intervals during the sewing of festoons.

It is further necessary to shift the fabric relatively to the festoon needles in the right moment and by the requisite amount and in a direction which is required at that moment by means of a suitably timed actuation of the cutting member, of the pressing lever, of the longitudinal slide and the transverse slide and of the two needles. Means have therefore to be provided to actuate all these organs and said means must derive their movements from the drive of the machine. In this manner means for actuating the longitudinal slide on the cross slide must cooperate with that slide which imparts a variable to and fro movement to the latter and actuating means must operate the transverse slide adapted to impart to the latter a to and fro movement that takes into account the necessary distance of the stitches from each other seen in the direction of movement of the transverse slide. The cutting member according to the invention consists of an upper knife and of a lower knife cooperating with each other in spite of the different movements which the two knives carry out. The upper knife is continuously angularly adjusted according to the shape of the festoons to be cut so that its edge is always a tangent to the arc of the festoon.

When an adjusting movement correspond-

ing to the shape to be cut is imparted to the upper knife by a controlling lever, the lower knife carries out exactly the same turning movement whereby a clean and safe cutting action like that of scissors is obtained. The cutter rod carries out upward and downward movements when the machine is driven, likewise the needles and the bar carrying the needles perform the known vertical reciprocating movements. The movements of the knife bar lead in comparison to the movements of the needle bar. When the needles are withdrawn from the fabric the shifting or feed movement of the fabric occurs and as soon as the latter is finished the cut is performed. After the latter the needles stitch again into the fabric. As soon as the needle bar is lifted so far that the needles are clear of the fabric the upper knife is already at such a height that the fabric enters a recess in the upper knife when it is shifted by suitable means. During the further turning of the machine the downwardly moving upper knife in cooperation with the lower knife, which is at that moment stationary in its uppermost position, cuts the fabric. After the cutting action is finished the lower knife performs a quick movement in the axial direction, i. e. in an oblique downward direction, so that the edge needle does not hit the lower knife during its downward movement during which movement it passes through a recess of the upper knife.

According to another feature of the invention the movements of the transverse slide and of the longitudinal slide are controlled by a cam disc which carries out a step by step movement. The shape of the circumference of the cam disc is determined by the shape of the festoon to be produced and the cam is used to cause the turning movement of the cutting member, i. e. of the upper and the lower knife, about its longitudinal axis. Furthermore the circumference of the cam disc is utilized to control the movement of the longitudinal slide in accordance with the shape of the arc of the festoon to be sewn and cut with the aid of a driving disc in which an arc shaped slide is so mounted that it is adapted to reciprocate. To this arc shaped slide the driving lever for the longitudinal slide is linked as well as a driving rod to which a reciprocating movement is imparted by suitable organs from the main driving shaft of the machine. The driving disc serves as a bearing for the arc-shaped slide and is adjusted by the cam disc.

The extent of the step by step adjustment of the cam disc may be adjusted to correspond to a desired distance of the stitches of the needles from each other so that the festoon stitches may be arranged closer to or farther away from each other.

Further through the intermediary of the

cam disc the distance of the needle stitches from each other may be automatically so influenced that the stitches at the beginning and at the end of each festoon may be closer to each other than in the middle part of the festoon arc.

Furthermore means may be provided by which the extent of the movement of the driving rod for the longitudinal slide can be adjusted at will.

The transverse slide may also be actuated immediately by the drive of the machine, for instance by the main shaft instead of being influenced by the cam disc. A device may be provided to completely cut out the action of the cam disc, whereby the radius of the festoon arc would become infinite, or in other words, the festoon arc would be a festoon edge which device permits at the same time the control of the driving disc and thereby also the cutting member by hand so that the production of irregular festoon arcs having a pattern which does not repeat itself and cannot be fixed by the cam disc circumference is rendered possible.

Constructional examples of the subject matter of the present invention are illustrated on the accompanying drawings, in which:

Fig. 1 shows the machine in elevation,

Referring now to the drawings in the frame 50 of the sewing machine for making festoons the driving shaft 51 is mounted in the known manner and projects beyond the frame to carry the fly wheel 52 and a driving pulley 53 which is rotated in a known manner from any source of power by means of a cord or any other suitable power transmission organ. A locking nut 54 serves in a known manner to establish and disconnect the operative connection between the driving pulley 53 and the driving shaft 51 so that the latter can be prevented from rotating. The driving shaft 51 is provided with two cranks and connecting rods 55 which impart rotation to the lower main shaft 56. The latter is mounted in the bearings 57.

The frame 50 is supported on the base plate 40 and carries at its front end 58 the guidances for the drive of the needle, of which the bar for actuating the needles is designated by 59. The frame 50 of the machine is further provided with two bearings 50 in which the shaft 19 is rotatably mounted. Oscillatory movements are imparted to the latter by an eccentric 61 fixed to the driving shaft 51 and the shaft 19 actuates the knife bar 15 by means of an arm 18 fixed to one end of the shaft 19. The knife bar is mounted in a bracket 16 supported by the front end 58 of the machine frame 50 and carries at its lower end the upper knife 2 cooperating with the lower knife 1 as is shown in detail in Figs. 12, 14 and 15. The lower knife is turnable in a suspended bearing 4 fixed to the base plate 40.

To one of the two connecting rods 55 a lever 62 is linked which cooperates with

a second lever 63 driving the axle 64. The latter is mounted in a bracket 65 fixed to the vertical part of the frame 50 and below the horizontal arm of said frame. The axle 64 projects beyond the bracket 65. The free end of the axle 64 carries a crank 66 to which a sliding block 68 (Fig. 6) is adjustably fixed by means of a winged nut 67; the sliding block 68 is further adjustable in two slotted arms 69 of a ring disc 70. The ring disc is turnable about an axle 71 and carries two pawls 72 arranged beside each other, (only one pawl is shown in Fig. 5), which are forced by a spring 74 to cooperate with a ratchet wheel 73. The latter is carried on the axle 71 which is rotatably mounted in a bracket 65. At the side of the ratchet wheel the cam disc 76 (Fig. 1) is mounted on the axle 71. The cam disc 76 and the ratchet wheel 73 are caused to rotate by a pin 75 fixed to the axle 71 (Fig. 11). At the end of the latter a nut 77 operated by hand is provided and serves to press the cam disc 76 against the ratchet wheel 73.

On the bracket 65 a carrier arm 78 is attached and a pin 79 is fixed on said arm. A double armed lever 80 is pivoted on the pin 79 and the lever 80 carries at one of its free ends a roller 81 pressed against the circumference of the cam disc 76 by the action of a spring 82 cooperating with the lower end of the double armed lever 80. The other end of the latter is linked to a lever 83 fixed to a further lever 84 (Fig. 7), the latter being rotatably mounted with one end in the base plate 40. As is shown in Fig. 7 the lever or link 83 is not directly fixed to the lever 84 but through the intermediary of a sleeve 85 which can be adjusted and fixed in position so that the movements of the double armed lever 80 caused by the rotation of the cam disc 76 generate a larger or smaller movement of the end of the lever 84 depending on the adjustment of the sleeve 85. The end of the lever 84 carries an axle 86 on which two sliding blocks 87 are provided, each of which is displaceable in a slot 88 of a crank 89 and can be adjusted nearer to or farther away from the auxiliary shaft 90. The two cranks 89 are fixed on the auxiliary shaft 90 and displace the latter when they are adjusted. A lever 91 is operatively connected to the axle 86 and the lever 91 is rocked by an eccentric 92 fixed on the main shaft 56. When the eccentric 92 is adjusted in a definite manner the lever 91 performs a movement of a constant extent. The angular extent through which the auxiliary shaft 90 rocks would be constant if the distance of the sliding blocks 87 from the centre of the auxiliary shaft 90 were constant. This distance is, however, influenced by the movements of the double armed lever 80 through

the intermediary of the link 83, the sleeve 85 and the lever 84. When these members cause the sliding blocks 87 to move away from the auxiliary shaft 90 the angle through which the auxiliary shaft 90 rocks becomes smaller and, vice versa, the angle becomes larger when the sliding blocks are nearer to the auxiliary shaft 90.

It is further possible to adjust the eccentric 92 in a known manner so that its throw gets larger or smaller. The movements of the auxiliary shaft 90 are now utilized to cause the movements of the transverse slide 31. To this end a crank 93 is fixed to the auxiliary shaft 90 and a connecting rod 47 is linked to the crank 93 and cooperating with the transverse slide 31, by means of a beak 95 (Fig. 12). The transverse slide 31 moves in a guide plate 39 which carries the stitch plate 48. The longitudinal slide 32 is movable in the transverse slide 31 and at right angles to the movements of the latter.

On the longitudinal slide 32 a lever 33 for pressing the fabric (Fig. 2) is mounted in the bearings 34 (Fig. 10) so that the pressure lever can be raised and lowered and is provided with a fork shaped foot 43 the lower side of which is roughened. This pressure lever surrounds the two festoon needles as well as the foot of a drag spring 37 which also surrounds the festoon needles on three sides and is fixed to the rod for pressing the fabric. For simplicity the festoon needles 41 and 49 are shown in their raised position in Figs. 1 and 4; the needle 49 is the so-called edge needle intended for stitching into the fabric at the edge of the festoon at which place the upper knife 2 cooperating with the lower knife 1 cuts the fabric.

The end of the pressure lever 33 remote from the foot of the pressure bar is connected to an actuating rod 97 which carries out reciprocating movements in the vertical direction at given moments in order to rock the pressure lever 33 in its bearings 34 and to thereby raise and lower the foot 43. The part of the pressure lever 33 carrying the foot 43 is influenced by a spring 35 which tends to press the foot 43 down onto the longitudinal slide 32. The part of the latter situated below the foot 43 is also roughened. The lower side of the foot and the part of the longitudinal slide below the foot may also be lined with rubber.

The movements of the pressure lever 33 are derived from an eccentric 96 on the main shaft 56 (Figs. 1 and 10). The eccentric rotates continuously with the rotating main shaft and therefore a rod 97 operatively connected to the eccentric 96 continuously moves up and down. The end of the rod 97 carries an abutment 98 which is at a certain distance from the pressure lever 33 when the eccentric 96 is in its highest posi-

tion as is shown in Fig. 1. When the eccentric 96 moves in the downward direction the rod 97 performs at first an idle stroke, in order to act on the end of the pressure lever 33 only when the eccentric 96 is in its lowest position and to raise the foot 43; after a short time the abutment 98 releases the lever 33 which moves downwards together with the foot 43 by the action of the spring 35.

With the longitudinal slide 32 the lever 45 cooperates and causes the former to carry out the necessary movements. The movements of the lever 45 are variable and are derived from the driving disc 99 (Fig. 2). The latter is turnable within a recessed disc 100 (Fig. 9). In the driving disc 99 an arc-shaped slide 101 is adjustably mounted as is shown in Fig. 2. The arc-shaped slide 101 carries a universal joint 102, to which a driving rod 103 is connected and which leads to a crank 104 (Fig. 1) loosely turnable on the auxiliary shaft 90 (Figs. 1 and 3). The movements of the crank 104 are caused by an eccentric arm 105 (Figs. 3 and 5) and are derived from an eccentric 106 fixed to the main shaft 56. This eccentric may also be adjustable in order to adjust the extent of the movements of the arm 105. The adjustment of the eccentric 106 may be performed in a known manner.

The movements of the arc-shaped slide 101 are transmitted by the driving disc 99 to the lever 45 and thereby to the longitudinal slide 32. The extent of these movements is influenced in that the driving disc 99 is angularly adjusted. To this end on the driving disc 99 (Fig. 9) a universal joint 107 is provided to which a rod 108 is linked, which is connected with the double armed lever 80 (Fig. 2). As has been mentioned above the movements of the lower end of the double armed lever 80 are controlled by the cam disc 76. When the roller 81 at the upper end of the double armed lever 80 is distanced from the axle 71 by the cam disc 76 the lever 80 swings around the pivot pin 79 in a clockwise direction. In consequence thereof the rod 108 actuates the driving disc 99 so that the latter turns somewhat in the anti-clockwise direction when looking from above. Simultaneously the arc-shaped slide 101 changes its position; the further the roller 81 is distanced from the axle 71 (Fig. 5) in accordance with the shape of the cam disc 76 the more the driving disc 99 (Fig. 2) is turned. Thereby the arc shaped slide is moved from the position 115 indicated in full lines in Fig. 2 into the position 114 indicated in chain dotted lines in Fig. 2.

In both positions 114 and 115 of the arc-shaped slide 101 i. e. in that shown in full lines as well as in that shown in chain-dotted lines, the lever 45 and thereby the longitudinal slide 32 perform their largest strokes at

the beginning and at the end of a festoon arc, and reference may be had to Fig. 20 of the drawing in which the various stitches of the needle are indicated by small circles connected by straight lines. It may further be seen from Fig. 20 that the feed of the fabric at the beginning of making a festoon is indicated by the distance 110 and in the middle part of the festoon by the distance 111, which distances are measured in the direction of movement of the longitudinal slide 32. The distance 110 is larger than the distance 111. Intermediate of the two illustrated positions 114 and 115 of the arc shaped slide the latter occupies such positions by which the movements of the longitudinal slides become smaller. In the middle position between the positions 114 and 115 the longitudinal slide does not move as the displacement of the arc-shaped slide 101 in connection with the position of the driving disc 99 gives no longitudinal displacement of the lever 45 and therefore of the longitudinal slide 32.

When the roller 81 of the double armed lever 80 has reached the position relative to the cam disc 76 shown in Fig. 23, the subsequent turning of the cam disc 76 will cause the roller 81 to spring into the position shown in Fig. 22. Thereby the lower end of the lever 80 is suddenly turned back in the anti-clockwise direction. The arc-shaped slide 101 springs from the position 114 indicated in chain-dotted lines into the position 115 shown in full lines and the operation starts again.

This sudden backward movement causes at the same time a sudden turning of the upper knife together with the lower knife 1; the knife 2 in this moment is in the corner of a festoon and must be turned through a large angle corresponding to the angle enclosed by two adjacent festoons, as is shown in Fig. 21, in order to pass from a finished festoon to the next festoon. Simultaneously with the gradual displacement of the arc-shaped slide 101 a gradual turning movement of the knife 2 to correspond to the shape of the festoon to be cut has been performed, so that the upper knife 2 and the lower knife 1 are always in the position of a tangent to the arc 117 of the festoon as is indicated in dotted lines 116 in Fig. 21. The movements of the double armed lever 80 are transmitted by means of the rod 118 (Fig. 2) the bell crank lever 119, the universal joint 120 and the link 121 to a pin 26 (Fig. 4) fixed on the control lever 22 of the upper knife 2. The bell crank lever 119 is turnable about an axle 122 which is mounted in a lateral extension 123 of the bracket 65.

It may further be seen from Fig. 20 that the smallest movements of the transverse slide 31 are at the beginning and at the end of a festoon arc whilst the largest move-

ments occur in the middle of the festoon arc so that the distance 113 is smaller than the distance 112. The stitches are closest to each other in the corners where two festoons meet.

On the base plate 40 a pin 124 is provided, about which a hand lever 125 is turnable; the latter has an edge eccentrically arranged to the pin 124 against which the lower part of the double armed lever 80 bears. This hand lever 125 permits the lever 80 to be brought out of contact with the cam disc 76 so that the roller 81 no longer cooperates with the circumference of the cam disc 76. Thereby the possibility exists of cutting out the movements of the longitudinal slide and the turning movements of the cutting member, i. e. of the upper knife 2 and lower knife 1, so that no arc-shaped festoons are made but festoons along a straight edge of the fabric. The hand lever 125 further permits the sewing of the festoons which have an irregular shape that is not repeated and can therefore not be fixed by a cam disc.

Obviously for festoons having a different shape to the festoon 116 shown in Fig. 21, a cam disc must be inserted which has a differently shaped circumference to that of the cam disc 76. It may further be mentioned that by the adjustment of the sliding block 68 by means of the winged nut, the step by step movement of the cam disc can be adjusted so that the latter performs one revolution in a shorter or longer time. In accordance therewith the length of the festoon gets shorter or longer and it creates the impression of being steeper or more stretched as the distances covered by the transverse slide become smaller or larger. The present machine is thus adapted to sew festoons of any shape, arcs, corners and the like.

Into the recess 3 (Figs. 14 and 15) of the lower knife 1 a fork 127 (Figs. 4 and 12) projects which is operatively connected to members driven from the main shaft 56 by means of an eccentric 128. The eccentric 128 is displaceable in a slot 129 provided in a lever 130, which is swingably arranged on an axle 131 suspended from the base plate 40. The lever 130 is linked at its free end to a rod 132 which in its turn is linked by means of a sleeve 133 to a guide rod 134. To the latter the fork 127 is rigidly connected so that when the rod 134 is lowered the fork 127 is lowered as well and causes the lowering movement of the lower knife 1. The guide rod 134 is axially movable in the bearing 4 fixed to the base plate 40. The lower knife 1 is freely turnable in the fork 127 so that it takes part in the turning movement transmitted to it by the upper knife 2. The eccentric 128 effects in a suitable moment a quick endwise downward movement of the lower knife 1, i. e. a movement in an oblique downward direction and this

takes place in the moment in which the upper knife is also in its upward position and the shifting or feed of the fabric is effected by the movement of the transverse slide 31. The fabric has entered the recess 12 of the upper knife by the shifting motion. Upon the further turning motion of the machine the upper knife 2 cooperating with the lower knife 1 cuts the fabric in the manner of scissors. As soon as the cutting action is finished the lower knife performs 70

5 might strike the lower knife. The upper part of the lower knife is provided with a long longitudinal slot 7 extending exactly along the axis of the knife, whereby two resilient prongs 8 and 9 are 10 formed, which are pressed towards each other so that the slot is comparatively narrow at its upper end. The end of the prong 8 is bevelled and forms the cutting edge of a pair of scissors. The prong 9 is also 15 bevelled at its end but is somewhat shorter than 8 so that the cut-off fabric is not clamped between the two prongs. The bottom 10 of the slot 7 extends at an acute angle to the axis of the knife so that fibres 20 of the fabric formed by the cutting action cannot lodge themselves within the slot.

The upper knife 2 is made of a flat piece and is provided besides the above mentioned recess 11 with a further recess 12 into which 25 the fabric to be cut enters when the fabric is shifted or fed. The part 13 is shaped to form the cutting edge of a scissors in a similar manner as the cutting edge of the lower knife.

30 The lower end 14 of the upper knife is pointed or chamfered so that it can be readily introduced into the resilient slot 7 of the lower knife. The upper knife is fixed with its upper end in the lower end of the

35 cutter bar 15, which is rotatably and axially displaceably mounted in a sleeve 23. The upward and downward movement of the cutter bar 15 necessary for the cutting action is imparted to the bar 15 by means of the 40 universal joints 17 (Fig. 6) and the rocking lever provided at the end of the shaft 19.

The sleeve 23 surrounding the cutter bar 15 is rotatably mounted at its ends 20 and 21 in the support 16 and carries at its lower end and rigidly connected to it the already mentioned controlling lever 22 (Fig. 4). To the latter a motion is imparted corresponding to the shape of the festoon to be cut by means of the pulling rod 121 from the 50 cam disc 76.

To the upper end of the sleeve 23 a lever 25 is fixed which carries a pin 26 engaging with an arm 24 which is splined to the cutter bar 15, whereby to the cutter bar and to the knife 2 a rotating or oscillating movement respectively is imparted which corresponds to the shape to be cut.

55 The needle bar performs the known upward and downward movement. The cutter bar performs a similar movement which leads relatively to the movement of the needle bar.

60 As soon as the needle bar 59 has performed its upward movement so far that the needles are withdrawn from the fabric, the

upper knife is also in its upward position and the shifting or feed of the fabric is effected by the movement of the transverse slide 31. The fabric has entered the recess 12 of the upper knife by the shifting motion. Upon the further turning motion of the machine the upper knife 2 cooperating with the lower knife 1 cuts the fabric in the manner of scissors. As soon as the cutting action is finished the lower knife performs 75 the above mentioned quick movement in an oblique downward direction. The flat pointed end 14 of the upper knife is guided in the lower knife and causes the latter to take part in the turning movement imparted 80 to the upper knife to correspond to the shape to be cut.

85 As soon as the needles 41 and 49 have stitched into the fabric the actuating rod 97 moves the rear end of the pressure lever 33 whereby the pressure foot is lifted off the fabric. The longitudinal slide 32 and the transverse slide 31 carry out the necessary movement to shift the fabric. When the needles are withdrawn from the fabric the 90 foot 43 moves in the downward direction, the fabric is thereby gripped and the shifting of the fabric in the necessary direction is effected, whereby the fabric is pulled along between the drag spring 37 and the 95 stitch plate 48.

The arrangement may also be made so that the foot is lifted after every second stitch.

In order to insure that the hem stitches 100 are nicely made, a member for laying the thread in position which may be called the thread guide is used as is shown in Fig. 1 and in a modified form in Figs. 24, 26 and 27. The thread guide 141 consists of a wire 105 bent to a hook 151 as is shown in Figs. 26 and 27. The upper end of the thread guide is swingably mounted on an arm 142 so that the thread guide is adapted to swing in the plane passing through both needles 41 and 49. At the needle bar 59 a roller 144 is provided against which the thread guide 141 is pressed by a spring 152. The arm 142 in Fig. 1 is fixed to the head 58 of the machine.

110 The upward and downward movement of the needle bar is caused by the driving shaft 51 provided with a head 136 at its end and a groove 137 being arranged in the latter with which a roller 138 cooperates serving to move the thread pulling member 162 in 115 the upward and downward direction. At its front end the head 136 is provided with a link 138' fixed to a sleeve 139, the latter being secured to the needle bar 59 so that the needle bar is moved up and down when 120 the shaft 51 rotates.

125 When the needle bar is in its lowest position the lower end of the thread guide 141 is aside of the needles. During the upward movement of the needle bar 59 the roller 144 130

glides along the thread guide 141, and as soon as a certain height is reached, the latter performs a movement towards the needles owing to its shape and under the influence of the spring 152. Owing to this movement the edge 158 of the hook forces the threads, which pass through the needles 41 and 49 into the fabric, to the side and as soon as the needle bar 59 moves downwardly the threads 159 and 160 are caught by the hook 151 of the thread guide 141. Thereby the thread 159 of the needle 41 is so presented to the edge needle 49 in the form of a loop that with the shifting of the fabric which occurs towards the observer in Figs. 1 and 26, the needle 49 enters the loop and the thread 159 is sewn to the fabric as may be seen in Fig. 26. The thread 160 of the needle 49 is then pulled slightly to one side so that it is beyond the path of the downwardly moving edge needle 49. Thereby an improvement of the stitch is obtained inasmuch as all the threads from the needles are gripped by the thread guide and are pulled aside of the plane of the needles so that a nice edge may be sewn.

In Fig. 24 the thread guide 141 is shown in connection with an ornamental stitch machine with which the needle bar 153 carries out a turning motion. A wheel 150 studed with pins serves in a known manner to turn the needle bar 153 as the wheel 150 is operatively connected to a sleeve 145. The upward and downward movement of the needle bar 153 is caused by means of a gliding ring 147, which grips the sleeve 145 and is in operative connection with the needle bar 153 by a pin 163 engageng a slot 148. The gliding ring 147 is rotatably mounted in a non-rotatable guide slide 149 surrounding the sleeve 145. On the slide 149 a pin 154 is provided with which the crank gear 155 cooperates and which serves to move the needle bar 153 up and down. The latter carries in its lower part the two needles 41 and 49 in a similar manner as is shown in Fig. 1. The arm 142 of the thread guide 141 is, however, not fixed to the frame 50 but to the turnable sleeve 145 and receives the same turning motion as the needles. The manner of operation of the device according to Figs. 24 and 25 is the same as described above with reference to Figs. 1, 26 and 27. The wheel 150 serves to turn the needle bar 153 and the thread guide 141 in accordance with the curvature to be sewn so that the stitches are radial to the latter.

Upon the main shaft 56 (Fig. 5) and on an extension of the connecting rod 55 a connecting rod 164 is provided which causes the rotation of the coupling member 167 by means of a drag crank gear 165 fixed to a shaft 166. At the other end of the shaft 166 a screw wheel 168 is fixed meshing with a screw wheel 169 on a transverse shaft 170

which drives the gripper of a ring shuttle (Fig. 4).

As will be seen in Figs. 17 and 18 in a gripper carriage 171 the gripper 172 is turnably mounted and within the latter the reel 70 casing 173 for the thread reel is arranged. At the lower part of the carriage 171, a pedestal 174 is provided in which the cover 175 of the reel casing, which is turnable about a pin 176 and locked by a hook 177, 75 is turnably mounted. The hook 177 is turnable about a pivot 178 and is provided with a lug 179 arranged in front of the cover 180 and prevents the removal of the latter as long as the cover 175 is in the position shown. Two locking pins 181 for the cover of the gripper are provided at the carriage for the gripper, the cover being provided with corresponding apertures.

Into the pedestal 174 a set screw with a 85 milled head 182 is screwed and presses with its head against two parallel arms 183 of a resilient stirrup 184 which presses with its two ends 185 on the cover in the direction towards the gripper bearing. The two arms 90 183 end in a handle 186 arranged at right angles to both arms and contacting with the lower part of the pedestal 174. After unscrewing the set screw 182 the resilient stirrup 184 may be easily pulled in the downward direction by means of the handle 186 and may be removed from the cover. The distance of the two arms from each other is slightly larger than the diameter of the threaded part 188, Fig. 18 of the set screw. 100 As may be seen in Fig. 18 the ends 185 of the gripper are not in the same plane as the two arms 183 and rest with their end parts only on the cover 180. The tightening of the set screw 182 causes an increase of the 105 pressure exerted by the ends 185 of the stirrup 184 against the cover 180, by unscrewing the set screw this pressure is released. By a pressure on the hook 177 against the action of the spring 187 the cover 180 is released after the cover 175 has been turned in the downward direction and it can be lifted off the locking pins 181. The cover may readily be placed in position and it takes up the same position again owing to 110 the two pins 181 and it is also secured against a displacement by said pins. 115

The shape of the resilient stirrup prevents the screw which holds the stirrup in position from being completely removed before the stirrup can be removed from the cover which is an essential advantage. Instead of making the stirrup of wire it may obviously be made by stamping.

As is shown in Figs. 1 and 5 a plate 192 is fixed by means of a screw to the upper part of the frame 50 of the machine. This plate is slightly arched and carries at its highest point a pin 194 fixed to it. Around the pin 194 a weight 195 provided with a 125

radial slot is placed. The lower side 197 of the weight is more vaulted than the upper face of the plate 192 so that an intermediate space 198 is present between the 5 weight and the plate 192. To the pin 194 a stirrup 199 is clamped the free end of which is formed as a guide hook 190 over which the thread 200 from the reel 201 passes. The latter is shown in Fig. 4. The 10 weight 195 clamps the thread 200 between the plate 192 and the edge 191 of the weight and acts thus as a brake to the thread 200. With this arrangement it is ensured that the 15 braking action is effective during the reel-ing.

The weight 195 is provided at its circumference with a recess 193 (Fig. 2) with 20 which a screw 189 engages in order to fix the position of the weight relatively to the plate 192.

The weight may also rest with its whole lower face on the upper face of the plate and the latter does not need to be arched and may have any other shape permitting a 25 braking action of the weight on the thread 200.

From the brake the thread passes over 30 a guide 202 and from there to another guide 203 arranged on the front part of the machine (Fig. 4) on the end of the shaft 19. From this guide the two threads 200 pass 35 through a thread tightening device fixed to the front of the head 58 of the frame 50 (Fig. 1). This tightening device is provided with two pairs of clamping discs 211 and 212 arranged on a common axle 213. On the latter a nut 204 is provided. Between the nut 204 and the foremost clamping disc of the pair of clamping discs 211 there is inserted a spiral spring 205, which 40 can be tightened more or less by a turning of the nut 204 so that the pressure by which the clamping discs tend to bear against each other can be increased or decreased.

45 Below the two pairs of clamping discs two guide members 208 for the threads 200 to be braked or tensioned respectively are turnably mounted on an axle 207. Each of the threads is now separately passed between the clamping discs of one pair of the latter and to one side of the axle 213, thereupon 50 they are slung around a guide member 208 and are again passed between a pair of clamping discs on the other side of the axle 213. With this guidance the clamping of 55 the thread is quite uniform as also with an unequal thickness of the thread a metallic contact between the clamping discs is avoided so that the festoon becomes more uniform.

Instead of the guide discs 208, obviously other guide members such as hooks, pins and the like may be provided.

60 In Figs. 28 and 29 a more compact arrangement is shown in which the guide mem-

bers are not singly attached to the front end of the machine frame but are united as a unitary structure and fixed as such to the frame. With this arrangement the guide members 209 are mounted on the plate 70 210 on which the pairs of clamping discs 211 and 212 are mounted through the intermediary of the axle 207. The guide members 209 are turnable about an axle 214. To 75 protect the spring 205 a sleeve 215 is provided in which the spring is lodged so that dust and dirt have no access to the spring. A guide hook 206 is mounted on the plate for the incoming threads.

The threads pass thus over the guide hook 80 206 then through the braking organ and arrive at the thread pulling member 162 from which they pass through an eyelet 216 provided with two apertures to the eyes of the needles.

The thread leading to the edge needle must be tensioned so that the threads bordering the edge of the festoon are tightly drawn, and its tension must be greater than that of the thread passing through the 90 needle 41. From this reason the thread for the edge needle is separately braked by the weight 195 of the braking device mounted on the frame 50.

In Figs. 4 only one reel 201 is shown. In 95 front of the latter a second reel is placed from which the thread to the edge needle is supplied. The other reel 201 is, however indicated in Fig. 1.

The seam is produced by the two needles 100 41 and 49 (Fig. 1), two needle threads and one lower thread, whereby the thread guide 141 catches the thread of the needle 41 and presents it to the needle 49 in such a manner that the latter stitches through the loop 105 of the thread caused by the thread guide which gives the connection of the two threads on the upper side of the fabric. At the lower side of the fabric the connection between the two needle threads is effected by the lower thread inasmuch as the 110 point of the gripper of the ring shuttle catches the two thread loops and introduces the lower thread into said loops.

The proper shifting movement of the fabric, which has to correspond to the different 115 shapes of the festoon to be produced, is imparted to the latter by means of the cross slide, of which 32 (Fig. 2) is the longitudinal slide and 31 denotes the transverse slide. To the longitudinal slide 32 is fixed the foot 120 43 of the pressure lever, which causes the shifting; the foot 43 is lifted off the fabric by the rod 97 (Fig. 1) after every performed stitch and after the shifting of the fabric has been effected, and after the slides 31 and 32 have returned into their initial positions the foot 43 is lowered again 125 on the fabric ready to perform the next shifting movement.

The shifting movement is carried out by the operator.

The formation of the festoons is caused by two movements: the movement in the direction in which the stitches are beside each other whereby a straight seam is effected and which is caused by the means 89-93 (Fig. 3) as hereinbefore described in detail and the movement at right angles to the first mentioned movement hereinbefore described and caused by the means 32, 45, 113, 114.

The fabric is cut along the edge of the festoon as soon as the fabric has on its feed motion entered the recess 12, (Figs. 14 and 15) of the upper knife by the cooperation of the latter with the lower knife which is then in its uppermost position. As soon as the cutting action is finished the needles 20 stitch into the fabric and the lower knife performs simultaneously a quick movement in an oblique downward direction to prevent the needle 49 from contacting with the lower knife.

The control of the movement of the fabric and of the knives is effected by the cam disc 76 if consecutive festoons having the same arc shape have to be made. The cam disc may be rendered ineffective and the shifting of the fabric may be performed by means of the hand lever 125, Fig. 2.

I claim:—

1. In a sewing machine for making festoons, in combination, two needles adapted to reciprocate in the vertical direction, a driving shaft, means interposed between said driving shaft and said needles to impart a reciprocating movement in the vertical direction to the latter, a cutting member 40 means adapted to shift the fabric comprising a transverse slide for shifting the fabric in the longitudinal direction thereof and a longitudinal slide for shifting the fabric in the transverse direction thereof, the cutting member being obliquely arranged and the point of intersection between the axis of the cutting member and the vertical plane of the needles being in the plane of movement of the fabric, a cam disc the circumference of which corresponds to the shape of the festoon to be made, an operative connection between said longitudinal slide and said cutting member and said cam disc, and means interposed between said cam disc and said driving shaft to impart a step by step movement to the former.

2. In a sewing machine for making festoons, in combination, two needles adapted to reciprocate in the vertical direction, a driving shaft, means interposed between said driving shaft and said needles to impart a reciprocating movement in the vertical direction to the latter, a cutting member, means adapted to shift the fabric comprising

ing a transverse slide for shifting the fabric in the longitudinal direction thereof and a longitudinal slide for shifting the fabric in the transverse direction thereof, the cutting member being obliquely arranged and the point of intersection between the axis of the cutting member and the vertical plane of the needles being in the plane of movement of the fabric, a cam disc the circumference of which corresponds to the shape of the festoon to be made, an operative connection between said longitudinal slide and said cutting member and said cam disc, which connection includes a driving disc, a two-armed lever cooperating with said cam disc and said driving disc and transmission means interposed between the driving disc and the longitudinal slide, and means interposed between said cam disc and said driving shaft to impart a step by step movement to the former.

3. In a sewing machine for making festoons, in combination, two needles adapted to reciprocate in the vertical direction, a driving shaft, means interposed between said driving shaft and said needles to impart a reciprocating movement in the vertical direction to the latter, a cutting member turnably mounted about its axis, means adapted to shift the fabric comprising a transverse slide for shifting the fabric in the longitudinal direction thereof and a longitudinal slide for shifting the fabric in the transverse direction thereof, the cutting member being obliquely arranged and the point of intersection between the axis of the cutting member and the vertical plane of the needles being in the plane of movement of the fabric, a cam disc the circumference of which corresponds to the shape of the festoon to be made, an operative connection between said longitudinal slide and said cutting member and said cam disc, which connection includes a driving disc, a two-armed lever cooperating with said cam disc and said driving disc and transmission means interposed between driving disc and the longitudinal slide, means interposed between said two armed lever and said cutting member for effecting the turning motion of the latter, and means interposed between said cam disc and said driving shaft to impart a step by step movement to the former.

4. In a sewing machine for making festoons, in combination, two needles adapted to reciprocate in the vertical direction, a driving shaft, means interposed between said driving shaft and said needles to impart a reciprocating movement in the vertical direction to the latter, a cutting member turnably mounted about its axis, means adapted to shift the fabric comprising a transverse slide for shifting the fabric in the longitudinal direction thereof and a longitudinal slide for shifting the fabric in the trans-

- verse direction thereof, the cutting member being obliquely arranged and the point of intersection between the axis of the cutting member and the vertical plane of the needles being in the plane of movement of the fabric, a cam disc the circumference of which corresponds to the shape of the festoon to be made, an operative connection between said longitudinal slide and said cutting member and said cam disc which connection includes a driving disc, a two armed lever cooperating with said cam disc and said driving disc and transmission means interposed between the driving disc and the longitudinal slide, an arc-shaped slide adapted to reciprocate in said driving disc, means interposed between said arc shaped slide and said longitudinal slide for operating the latter, a driving rod linked to said arc-shaped slide and adapted to carry out reciprocating movements, and means interposed between said cam disc and said driving shaft to impart a step-by-step movement to the former.
5. In a sewing machine for making festoons, in combination, two needles adapted to reciprocate in the vertical direction, a driving shaft, means interposed between said driving shaft and said needles to impart a reciprocating movement in the vertical direction to the latter, a cutting member turnably mounted about its axis, means adapted to shift the fabric comprising a transverse slide for shifting the fabric in the longitudinal direction thereof and a longitudinal slide for shifting the fabric in the transverse direction thereof, the cutting member being obliquely arranged and the point of intersection between the axis of the cutting member and the vertical plane of the needles being in the plane movement of the fabric, a cam disc the circumference of which corresponds to the shape of the festoon to be made, an operative connection between said longitudinal slide and said cutting member and said cam disc which connection includes a driving disc, a two armed lever cooperating with said cam disc and said driving disc and transmission means interposed between the driving disc and the longitudinal slide, a slotted member, a sliding block in said slot, a connection between one end of said double armed lever and said sliding block, an axle an eccentric cooperating with said slotted member, mounted on said axle, a crank on said axle an operative connection between said crank and said transverse slide to cause the variable movements of the latter, and means interposed between said cam disc and said driving shaft to impart a step-by-step movement to the former.
7. In a sewing machine for making festoons, in combination, two needles adapted to reciprocate in the vertical direction, a driving shaft, means interposed between said driving shaft and said needles to impart a reciprocating movement in the vertical direction to the latter, a cutting member turnably mounted about its axis, means adapted to shift the fabric comprising a transverse slide for shifting the fabric in the longitudinal direction thereof and a longitudinal slide for shifting the fabric in the transverse direction thereof, the cutting member being obliquely arranged and the point of intersection between the axis of the cutting member and the vertical plane of the needles being in the plane of movement of the fabric, a cam disc the circumference of which corresponds to the shape of the festoon to be made, an operative connection between said longitudinal slide and said cutting member and said cam disc which connection includes a driving disc, a two armed lever cooperating with said cam disc and said driving disc and transmission means interposed between the driving disc and the longitudinal slide, means interposed between said two armed lever and said cutting member for effecting the turning motion of the latter, a resilient member adapted to hold said two armed lever in contact with said cam disc, and means interposed between said cam disc and said driving shaft to impart a step-by-step movement to the former.
6. In a sewing machine for making festoons, in combination, two needles adapted to reciprocate in the vertical direction, a driving shaft, means interposed between said driving shaft and said needles to impart a reciprocating movement in the vertical direction thereof, a cutting member turnably mounted about its axis, means adapted to shift the fabric comprising a transverse slide for shifting the fabric in the longitudinal direction thereof and a longitudinal slide for shifting the fabric in the transverse direction thereof, the cutting member being obliquely arranged and the point of intersection between the axis of the cutting member and the vertical plane of the needles being in the plane movement of the fabric, a cam disc the circumference of which corresponds to the shape of the festoon to be made, an operative connection between said longitudinal slide and said cutting member and said cam disc which connection includes a driving disc, a two armed lever cooperating with said cam disc and said driving disc and transmission means interposed between the driving disc and the longitudinal slide, an arc-shaped slide adapted to reciprocate in said driving disc, means interposed between said arc-shaped slide and said longitudinal slide for operating the latter, an eccentric on said driving shaft, a connection between said eccentric and said arc-shaped slide for reciprocating the latter, and means interposed between said cam disc and said driving shaft to impart a step-by-step movement to the former.

ing shaft to impart a step-by-step movement to the former.

8. In a sewing machine for making festoons, in combination, two needles adapted to reciprocate in the vertical direction, a driving shaft, means interposed between said driving shaft and said needles to impart a reciprocating movement in the vertical direction to the latter, a cutting member turnably mounted about its axis, means adapted to shift the fabric comprising a transverse slide for shifting the fabric in the longitudinal direction thereof and a longitudinal slide for shifting the fabric in the transverse direction thereof, the cutting member being obliquely arranged and the point of intersection between the axis of the cutting member and the vertical plane of the needles being in the plane of movement of the fabric, a cam disc the circumference of which corresponds to the shape of the festoon to be made, an operative connection between said longitudinal slide and said cutting member and said cam disc which connection includes a driving disc, a two armed lever cooperating with said cam disc and said driving disc and transmission means interposed between the driving disc and the longitudinal slide, a slotted member, a sliding block in said slot, a swingably mounted lever, a connection between the free end of said lever and the sliding block, a sleeve displaceable along said lever and linked to the lower end of said double armed lever, an axle, an eccentric cooperating with said slotted member mounted on said axle, a crank on said axle, an operative connection between said crank and said transverse slide to cause the variable movements of the latter, and means interposed between said cam disc and said driving shaft to impart a step-by-step movement to the former.

9. In a sewing machine for making festoons, in combination, two needles, a driving shaft, means interposed between said driving shaft and said needles to impart to the latter a reciprocating movement in the vertical direction, an obliquely positioned cutting device, means adapted to shift the fabric comprising a transverse slide for shifting the fabric in the longitudinal direction and a longitudinal slide for shifting the fabric in the transverse direction thereof, a cam disc the circumference of which corresponds to the shape of the festoon to be made, an axle on which said cam disc is exchangeably mounted, a nut for holding said cam disc in position, an operative connection between said longitudinal slide and said cutting device and said cam disc, and means interposed between said cam disc and said driving shaft to impart a step-by-step movement to the former.

10. In a sewing machine for making festoons, in combination, two needles, a driv-

ing shaft, means interposed between said driving shaft and said needles to impart to the latter a reciprocating movement in the vertical direction, an obliquely positioned cutting device, means adapted to shift the fabric comprising a transverse slide for shifting the fabric in the longitudinal direction and a longitudinal slide for shifting the fabric in the transverse direction thereof, a cam disc the circumference of which corresponds to the shape of the festoon to be made, an operative connection between said longitudinal slide and said cutting device and said cam disc, a ratchet wheel connected to said cam disc, pawls cooperating with said ratchet wheel, a member having a slot and cooperating with said pawls, a sliding block in said slot and adapted to be adjusted by hand, and means interposed between the driving shaft and said sliding block controlling the movement of the latter and imparting thereby a step-by-step movement to said cam disc.

11. In a sewing machine for making festoons, in combination, two needles, a driving shaft, means interposed between said driving shaft and said needles to impart to the latter a reciprocating movement in the vertical direction, an obliquely positioned cutting device, means adapted to shift the fabric comprising a transverse slide for shifting the fabric in the longitudinal direction and a longitudinal slide for shifting the fabric in the transverse direction thereof, a cam disc the circumference of which corresponds to the shape of the festoon to be made, an operative connection between said longitudinal slide and said cutting device and said cam disc, which connection includes a driving disc, a two-armed lever cooperating with said cam disc and said driving disc and transmission means interposed between the driving disc and the longitudinal slide, a hand lever cooperating with said double armed lever and adapted to interrupt the operative engagement between the latter and the cam disc.

12. In a sewing machine for making festoons, in combination, two needles, a driving shaft, means interposed between said driving shaft and said needles to impart to the latter a reciprocating movement in the vertical direction, an obliquely positioned cutting device, consisting of an upper end and a lower knife turnably about their axis and endwise displaceable, the upper end of the lower knife having a long slot formed by two resilient prongs and the upper knife entering said slot for cooperating with the lower knife in a scissors like manner during the cutting action and the lower knife being turned by the turning motion of the upper knife, means adapted to shift the fabric comprising a transverse slide for shifting the fabric in the longitudinal direction

and a longitudinal slide for shifting the fabric in the transverse direction thereof, a cam disc the circumference of which corresponds to the shape of the festoon to be 5 made, an operative connection between said longitudinal slide and said cutting device and said cam disc, and means interposed between said cam disc and said driving shaft to impart a step-by-step movement to the 10 former.

13. In a sewing machine for making festoons, in combination, two needles, a driving shaft, means interposed between said driving shaft and said needles to impart to the 15 latter a reciprocating movement in the vertical direction, an obliquely positioned cutting device consisting of an upper knife and a lower knife turnable about their axis and endwise displaceable, the upper end of 20 the lower knife having a long slot formed by two resilient prongs and the upper knife entering said slot for cooperating with the lower knife in a scissors like manner during the cutting action and the lower knife 25 being turned by the turning motion of the upper knife, the upper knife being provided with a first recess for the needle to pass through and with a second recess one edge part of which is shaped as a cutting edge, 30 and into which the fabric enters, and the lower end of the upper knife being chamfered, means adapted to shift the fabric comprising a transverse slide for shifting the fabric in the longitudinal direction 35 and a longitudinal slide for shifting the fabric in the transverse direction thereof, a cam disc the circumference of which corresponds to the shape of the festoon to be made, an operative connection 40 between said longitudinal slide and said cutting device and said cam disc, and means interposed between said cam disc and said driving shaft to impart a step-by-step movement to the former.

45 14. In a sewing machine for making festoons, in combination, two needles, a driving shaft, means interposed between said driving shaft and said needles to impart to the latter a reciprocating movement in the vertical direction, and obliquely positioned cutting device consisting of an upper and a lower knife turnable about their axis and endwise displaceable, the upper end of the lower knife having a long slot formed by 50 two resilient prongs and the upper knife entering the said slot for cooperating with the lower knife in a scissors like manner during the cutting action and the lower knife being turned by the turning motion of the upper knife, the bottom of said slot being inclined and one of the prongs being shorter than the other and the prongs being pressed against each other for exerting a pressure 55 on the upper knife, means adapted to shift the fabric comprising a transverse slide for

shifting the fabric in the longitudinal direction and longitudinal slide for shifting the fabric in the transverse direction thereof, a cam disc the circumference of which corresponds to the shape of the festoon to be 70 made, an operative connection between said longitudinal slide and said cutting device and said cam disc, and means interposed between said cam disc and said driving shaft to impart a step-by-step movement to the 75 former.

15. In a sewing machine for making festoons, in combination, two needles, a driving shaft, means interposed between said driving shaft and said needles, to impart to the 80 latter a reciprocating movement in the vertical direction, an obliquely positioned cutting device consisting of an upper knife and a lower knife turnable about their axis and endwise displaceable, means to impart a quick movement in the downward direction to the lower knife when the needles have entered the fabric, means adapted to shift the fabric comprising a transverse slide for shifting the fabric in the longitudinal direction 85 and a longitudinal slide for shifting the fabric in the transverse direction thereof, a cam disc, the circumference of which corresponds to the shape of the festoon to be made, an operative connection between said longitudinal slide and said cutting device and said cam disc, and means interposed between said cam disc and said driving shaft to impart a step-by-step movement to the former.

16. In a sewing machine for making festoons, in combination, two needles, a driving shaft, means interposed between said driving shaft and said needles to impart to the latter a reciprocating movement in the vertical direction, an obliquely positioned cutting device, a longitudinal slide, a lever adapted to press on the fabric and swingably mounted on said longitudinal slide, means to raise and lower said lever at regular intervals, means adapted to shift the fabric comprising a transverse slide for shifting the fabric in the longitudinal direction and a longitudinal slide for shifting the fabric in the transverse direction thereof, a cam disc the circumference of which corresponds to the shape of the festoon to be made, an operative connection between said longitudinal slide and said cutting device and said cam disc, and means interposed between said cam disc and said driving shaft to impart a step-by-step movement to the former.

17. In a sewing machine for making festoons, in combination, two needles, a driving shaft, means interposed between said driving shaft and said needles to impart to the latter a reciprocating movement in the vertical direction, an obliquely positioned cutting device, means adapted to shift the fabric comprising a transverse slide for shifting the fabric in the longitudinal direction 110 115 120 125 130

- and a longitudinal slide for shifting the fabric in the transverse direction thereof, a cam disc the circumference of which corresponds to the shape of the festoon to be made, and a thread guide swingably arranged in the plane of the needles and provided with a hook shaped end to grip the threads for moving them slightly sideways.
18. In a sewing machine for making festoons, in combination, two needles, a needle bar carrying said needles, a driving shaft, means interposed between said driving shaft and said needle bar to impart to the latter a reciprocating movement in the vertical direction, an obliquely arranged cutting device, means adapted to shift the fabric comprising a transverse slide for shifting the fabric in the longitudinal direction and a longitudinal slide for shifting the fabric in the transverse direction thereof, a cam disc the circumference of which corresponds to the shape of the festoon to be made, an operative connection between said longitudinal slide and said cutting device and said cam disc, means interposed between said cam disc and said driving shaft to impart a step-by-step movement to the former, and a thread tensioning device comprising at least one pair of clamping discs and guide members laterally of said clamping discs.
19. In a sewing machine for making festoons, in combination, two needles, a driving shaft, means interposed between said driving shaft and said needle bar to impart to the latter a reciprocating movement in the vertical direction, an obliquely arranged cutting device, means adapted to shift the fabric comprising a transverse slide for shifting the fabric in the longitudinal direction and a longitudinal slide for shifting the fabric in the transverse direction thereof, a cam disc the circumference of which corresponds to the shape of the festoon to be made, an operative connection between said longitudinal slide and said cutting device and said cam disc, means interposed between said cam disc and said driving shaft to impart a step-by-step movement to the former, a thread guide swingably arranged in the plane of the needles and provided with a hook shaped end to grip the threads for moving them slightly sideways, a roller mounted on said needle bar, and a spring cooperating with said roller and holding the latter in engagement with said thread guide.
20. In a sewing machine for making festoons, in combination, two needles, a needle bar carrying said needles, a driving shaft, means interposed between said driving shaft and said needle bar to impart to the latter a reciprocating movement in the vertical direction, an obliquely arranged cutting device, means adapted to shift the fabric comprising a transverse slide for shifting the fabric in the longitudinal direction and a longitudinal slide for shifting the fabric in the transverse direction thereof, a cam disc the circumference of which corresponds to the shape of the festoon to be made, an operative connection between said longitudinal slide and said cutting device and said cam disc, means interposed between said cam disc and said driving shaft to impart a step-by-step movement to the former, a thread tensioning device comprising at least one pair of clamping discs and a guide member arranged laterally of said clamping discs and fixed to a plate serving for mounting the lower of said clamping discs and a further guide member fixed to said plate and arranged on the other side of said clamping disc on which said first guide member is arranged.
21. In a sewing machine for making festoons, in combination, two needles, a driving shaft, means interposed between said driving shaft and said needles to impart to the latter a reciprocating movement in the vertical direction, an obliquely positioned cutting device, means adapted to shift the fabric comprising a transverse slide for shifting the fabric in the longitudinal direction and a longitudinal slide for shifting the fabric in the transverse direction thereof, a cam disc the circumference of which corresponds to the shape of the festoon to be made, an operative connection between said longitudinal slide and said cutting device and said cam disc, means interposed between said cam disc and said driving shaft to impart a step-by-step movement to the former, and a thread tensioning device comprising at least one pair of clamping discs and a guide member arranged laterally of said clamping discs and fixed to a plate serving for mounting the lower of said clamping discs and a further guide member fixed to said plate and arranged on the other side of said clamping disc on which said first guide member is arranged.
22. In a sewing machine for making festoons, in combination, two needles, a driving shaft, means interposed between said driving shaft and said needles to impart to the latter a reciprocating movement in the vertical direction, an obliquely positioned cutting device, means adapted to shift the fabric comprising a transverse slide for shifting the fabric in the longitudinal direction and a longitudinal slide for shifting the fabric in the transverse direction thereof, a cam disc the circumference of which corresponds to the shape of the festoon to be made, an operative connection between said longitudinal slide and said cutting device and said cam disc, means interposed between said cam disc and said driving shaft to impart a step-by-step movement to the former, an annular gripper, a cover above said gripper, pins to secure said cover against being displaced, a resilient stirrup pressing against said cover, and a screw.

threaded device for holding said stirrup in position.

23. In a sewing machine for making festoons, in combination, two needles, a driving shaft, means interposed between said driving shaft and said needles to impart to the latter a reciprocating movement in the vertical direction, an obliquely positioned cutting device, means adapted to shift the fabric comprising a transverse slide for shifting the fabric in the longitudinal direction and a longitudinal slide for shifting the fabric in the transverse direction thereof, a cam disc the circumference of which corresponds to the shape of the festoon to be

made, an operative connection between said longitudinal slide and said cutting device and said cam disc, means interposed between said cam disc and said driving shaft to impart a step-by-step movement to the former, an annular gripper, a cover above said gripper, pins to secure said cover against being displaced, a resilient stirrup having two parallel arms pressing against said cover, and ending in a handle arranged at right angles to the arms, and a screw for holding said stirrup in position.

In testimony whereof I affix my signature.

KARL MISCHKE.
